UNITED STATES PATENT OFFICE.

LOUIS STEINBERGER, OF NEW YORK, N. Y.

INSULATOR.

No. 827,187.

Specification of Letters Patent.

Patented July 6, 1909.

Application filed September 16, 1907. Serial No. 393,088. ~~REISSUED~~

To all whom it may concern:

Be it known that I, LOUIS STEINBERGER, a citizen of the United States, and a resident of the city of New York, borough of Brooklyn, in the county of Kings and State of New York, have invented a new and Improved Insulator, of which the following is a full, clear, and exact description.

My invention relates to insulators employed in general electrical work and more particularly for service in high tension work, and in instances where the insulator is subjected to great mechanical strain and high voltage.

Among the several objects of my invention are the following: I, to encircle the metallic tension members with several concentric tubular members of insulating material, thereby increasing the dielectric properties of the insulator; II, to insulate certain internal parts of the structure with insulating material having properties adapting it to resist mechanical stresses, and to cover the outer portions of the device with insulating material rendering it fireproof, waterproof, and otherwise suitable for out-door exposure. III, to increase the mechanical strength of the insulator by providing it with disks having bridges integral therewith and having shapes and relative positions giving exceptional advantages as regards mechanical stresses; IV, to enable the insulator to be assembled without the necessity for disconnecting the tension members from any fastenings which may engage them; V, to provide certain parts of the insulating material with tubular portions integral therewith and extending along the tension members for the purpose of protecting points beyond the bounds of the particular body of insulating material with which they are integrally connected; VI, to provide the tension members with fastenings of an improved kind which may be placed in position after the tension members are placed approximately in position; VII, to sink the fastening members last mentioned into the body portions of the device for the purpose of more readily holding the fastening members in position; VIII, to give the exterior of the insulator such conformity as to tend more effectively to prevent arcing and surface leakage, and also to adapt the device for supporting wires in various relations; IX, to provide tension members with fastening members of such conformity as to enable one to attach or remove

them at will; X, to provide tension disks having portions raised relatively to the surface upon which fastenings rest, so as to retain the fastenings more securely in place when the device is put under stress. XI, to provide a disk insulator of such construction that it may be connected to other insulators either rigidly or flexibly.

Reference is to be had to the accompanying drawings forming a part of this specification, in which similar characters of reference indicate corresponding parts in all the figures.

Figure 1 is a vertical, central section through an insulator made in accordance with my invention and showing the relative positions of the inner body of insulating material and the outer body of insulating material, the inner body of insulating material having tubular portions extending through it, this view also showing how the tension members are connected with the metallic disks and with the insulating material of the insulator; Fig. 2 is a vertical cross section taken upon the line 2—2 of Fig. 1 and showing more particularly the arrangement of the tension members and the insulating members; Fig. 3 is a vertical section somewhat similar to Fig. 1 but showing the outer covering of insulating material as omitted, the device in this figure being capable of use, if desired, without the addition of the outer member of insulating material shown in Fig. 1; Fig. 4 is a perspective of one of a pair of metallic disks, for receiving the mechanical stress due to the pull upon the device when in use, this view showing the various apertures necessary for connecting the various parts properly in position; Fig. 5 is a fragmentary perspective somewhat similar to the top of Fig. 4 and showing in addition a portion of one of the tension members, and the fastening member for preventing the withdrawal of the tension member from the disk upon which it exerts mechanical stress.

A pair of metallic disks 6 are each provided with two circular apertures 7 of considerable size and with two smaller apertures 8 also circular, the disk being further provided with annular shoulders 9 disposed adjacent to the apertures 8. In effect, the apertures 8 are holes provided with countersinks into which they merge. Each disk 6 is provided with a bridge 7^a integral therewith, this bridge simply representing the portion of material remaining between the apertures 7. Each disk 6 is further provided with thin por-

tions 10 representing the material left between each aperture 7 and the adjacent edge of the disk. A tension member 11 is provided with flattened lugs 12 integral therewith and connected together by a bolt 13. This bolt 13 extends through the lugs 12 and is provided with a head 14 and with a revolvable nut 15 whereby it may be connected to the wire, cable or analogous member to be used as a support for the insulator. The tension member 11 is provided with two prongs 16, each having a head 17 integral therewith and produced thereupon by upsetting the ends of the prongs. Washers 18 each having a slot 19, are made of a size enabling them to be fitted against the shoulders 9 (see Fig. 5). The slot 19 of each washer 18 is preferably of such width that the washer must be driven forcibly upon the prong 16 in order to grip it tightly.

At 20, 20^a are two disks of insulating material each flattened upon one side, these disks being of a kind adapted to resist compression stresses. When the disks 20, 20^a are fitted together (see Fig. 3) they constitute, to all intents and purposes, a single disk provided with a comparatively wide and thin edge.

When the parts are assembled, as herein-after described, and as indicated in Fig. 3, they comprise practically a composite body of insulating material provided with holes 21 extending entirely through it, and further provided with tubular extensions 22 and with webs 23, these webs, one at each end of the insulator, crossing each other. A socket 24 is mounted integrally upon a tension member 25, the latter being divided into two prongs 16^a exactly like the prongs 16. The socket 24 is provided with a hole 26 extending diametrically through it and is provided internally with a thread 27 for the purpose of engaging a threaded bolt or other member, in order to enable one end of the insulator to be suspended or otherwise sustained, or connected with any other member.

In order to assemble the parts shown in Fig. 3, the disks 20 and 20^a, of insulating material, are fitted respectively with the two metal disks 6, the latter being so disposed that the walls 18 of one of them are substantially in registry with the aperture 7 of the other. In this manner the apertures 7^a extend crosswise of each other. The prongs of the tension members are next inserted, the heads 17 being passed through the holes 21, 8 and the washers 18 being driven laterally upon the prongs. The device is now ready for use if no further insulation than that indicated in Fig. 3 is required. It is desirable, however, to provide further insulation and also to prevent the entrance of water into the parts shown in Fig. 3. In such event, I add a body 28 of insulating material, shaping it so as to form disks 29, and further provide it with ends 30 and with annular corru-

gations 31, 32. The disks 29 are separated from each other by an annular groove 33 which may be used to advantage in receiving a wire 33^a. The corrugations 31, 32, are separated by grooves 34, 35. The grooves 34, 35 may also be used to receive one or more wires. The corrugations 31, 32, and the disks 29 facilitate the dripping of moisture and also avoid the tendency for the current to leak. If for any reason it may be necessary to let the insulator down to the ground it has a tendency to remain upon the edges of the disks 29 and thus to avoid the necessity for the wires, cables or guys coming into contact with the earth.

The outer member 28 of insulating material is preferably added after the other parts of the device are assembled, as shown in Fig. 3, and may be applied by forcing the insulating material while in a plastic condition, into and around the parts shown in Fig. 3. The material of the outer insulating body is forced into the holes 21 and 8 so as to constitute tubular members extending practically throughout the entire length of the inner body of insulating material, including the tubular extensions 22 of the same. By this means each prong 16 is encircled by a sleeve 21^a of insulating material having one dielectric constant. These sleeves being encircled by a single body of insulating material having a different dielectric constant, and this body being enveloped in a mass of insulating material having the same dielectric constant as the sleeve 21^a, as will be understood from Fig. 2. The ends 30 of the outer body of insulating material may be about at flush with the inner edge of the socket 24 at one end of the strain and may be caused to envelop a considerable part of the tension member 11 at points extending considerably outward from the center of the insulator.

It will be noted from the above description that I have produced an insulator affording considerable mechanical strength in proportion to the sizes and quantities of material used, and also affording high dielectric qualities. The efficiency of the insulator may be increased by building one part of it with a view to standing great mechanical stresses coupled with considerable dielectric strains, and yet constructing another portion of the insulator of insulation adapted to render the construction waterproof and fireproof. Any number of these insulators may be connected together or connected to insulators of different form in series so as to increase the aggregate insulation. The insulators may be arranged with their axes either horizontal or vertical.

I do not limit myself to the exact form, nor to the details of any or all of the parts above shown and described, nor do I limit myself to any particular combination of the parts,

nor to the use of any prescribed materials, but prefer to use for the outer body portion shown in Fig. 1 the material well known in this art as "electrode"; for the inner insulating portion shown in Fig. 3 I may employ either electrode or a more distinctive waterproof and fireproof material, or any other suitable material.

It will be evident to those skilled in the art that many changes in the construction, form and arrangement of the parts may be resorted to without departing from the spirit or scope of my invention.

Having thus described my invention, I claim as new and desire to secure by Letters Patent:—

1. An insulator, comprising a plurality of disks of insulating material provided with holes, tension members provided with prongs 20 for extending through said holes, and further provided with heads, and fastening members for engaging said prongs and thus preventing the retrogression of said heads through said holes.

2. An insulator, comprising a plurality of metallic disks, a body of insulating material engaging said disks and preventing electrical communication therebetween, said body of insulating material being provided with 30 holes, tension members extending through said holes and provided with heads, and washers provided with slots and disposed adjacent to said heads for preventing retrogression of the latter through said holes.

3. An insulator, comprising a body, tension members of conducting material, and an outer covering of insulating material provided with a body portion having annular corrugations encircling it, and also having 40 disks integral with it, said disks being disposed in close proximity to each other and merging together at one point.

4. An insulator, comprising a body portion of insulating material provided with 45 holes, tension members provided with prongs extending through said holes, and further provided with enlarged portions upon the ends of said prongs, said enlarged portions being of such size as to enable them to pass 50 through said holes, and fastening members for preventing the retrogression of said heads through said holes.

5. An insulator, comprising a body portion of insulating material provided with 55 tubular extensions of insulating material projecting outwardly from the ends of said body portion, said body portion being further provided with webs connecting together certain of said tubular extensions, and tension members 60 extending entirely through said body portion of insulating material and through said tubular extensions, said tension members being further provided with means for preventing their withdrawal from said body 65 portion.

6. An insulator, comprising a pair of disks of insulating material, each provided with tubular extensions mounted thereupon and rigid relatively thereto, the tubular extensions of one disk being staggered relatively 70 to those of another, and a plurality of metallic members provided with portions extending through said disks of insulating material and through said tubular extensions.

7. In an insulator, the combination of a 75 plurality of disks of insulating material, each provided with a hole extending entirely through it, said disks being in registry with each other, metallic members extending through said holes and provided with 80 means to prevent their withdrawal through said holes, and a body of insulating material enveloping said disks and portions of said metallic members, said body of insulating material extending integrally into said holes 85 and disposed intermediate said metallic members and said disks.

8. An insulator, comprising a body of insulating material provided with tubular extensions integral therewith, and further provided with holes extending through said body and through said tubular extensions, tension members extending through said holes and tubular extensions, and means for preventing 90 the withdrawal of said tension members 95 from said body of insulating material.

9. An insulator, comprising a plurality of disks of metal each provided with apertures and with a bridge bounding said apertures, the bridge of one disk being disposed across 100 the bridge of another disk, each disk being provided with holes disposed adjacent to the ends of the bridge of that disk, a body of insulating material disposed intermediate said disks, and tension members extending through 105 said holes in said disks of metal and through said body of insulating material.

10. An insulator, comprising a main body of insulating material provided with a disk and with extensions integral therewith, and 110 further provided with holes extending through said main body and continued through said extensions, tension members following said holes and thus extending through said main body of insulating material and through said extensions, and means 115 for securing said tension members relatively to said body of insulating material.

11. An insulator, comprising a plurality of metallic disks provided with apertures, 120 and also provided with holes, a member of insulating material disposed intermediate said disks and provided with integral portions extending through said apertures, and tension members extending through said 125 holes and through said extending portions.

12. An insulator, comprising a plurality of metallic disks, tension members connected therewith, and means for insulating said metallic disks from each other, said means 130

including a body of insulating material extending outwardly and formed into a comparatively large disk.

13. An insulator, comprising a body of insulating material provided with a plurality of disks comparatively large in diameter merging together and made integral with said body of insulating material, and strain members connected with said body portion.

10 14. An insulator, comprising a plurality of disks of insulating material, said disks being of comparatively large diameter and disposed closely together for the purpose of engaging opposite portions of a conductor disposed intermediate said disks.

15 15. An insulator, comprising a plurality of disks of insulating material, said disks being of comparatively large diameter and disposed closely together, so that one merges 20 into the other, and means for connecting

tension members with said disks for the purpose of supporting the latter.

16. An insulator, comprising a plurality of disks each made of insulating material and provided with holes, said holes being 25 spaced a little distance from the outer edges of the disk so as to leave a portion of insulating material intermediate said holes and one edge of said disk at the points thereof nearest to said edges, and tension members 30 extending through said holes and insulated from each other.

In testimony whereof I have signed my name to this specification in the presence of two subscribing witnesses.

LOUIS STEINBERGER.
